(57) **CLAIM**

The ornamental design for support assemblied with a thermal printer and applied to a kiosk, as shown and described in the drawings.

DESCRIPTION

FIG. 1 is a perspective view of the support assemblied with a thermal printer and applied to a kiosk showing my new design.

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is the second perspective view thereof;

FIG. 9 is the third perspective view thereof; and,

FIG. 10 is the fourth perspective view thereof.

This patent application is applied for a partial design in USA, so it will be understood that the dash lines presented in the drawings are for illustration only, and do not form a part of the claimed design.
